UNITED STATES PATENT OFFICE.

HENRY W. LORMOR, OF CLEVELAND, OHIO, ASSIGNOR TO WILLARD STORAGE BATTERY COMPANY, OF CLEVELAND, OHIO, A CORPORATION OF WEST VIRGINIA.

BRUSHING MACHINE.

Application filed February 26, 1923. Serial No. 621,256.

This invention relates to what may be termed a brand brusher.

It is customary in the manufacture of certain devices such as storage batteries, to burn by means of a heated die the brand or trade mark into battery boxes which are generally made of wood. Generally also the lines or grooves of the brand burned into the box are painted so that they will stand out sharply or be readily seen. This makes it necessary or desirable that the brand be brushed or freed of the carbon or charred wood produced in the branding operation by the heated die. Heretofore the boxes branded in this manner have been freed or cleared of the carbon by brushing the boxes manually with a brush.

The object of the present invention is to provide a machine through which the branded boxes may be passed at a rapid rate and which will while the boxes are traveling through the machine entirely clear or brush free of the boxes the carbon that adheres to the boxes at the brand.

A still further object is to provide a machine which will accomplish this work in a rapid as well as satisfactory manner so that the operation may be performed inexpensively as compared with the hand brushing method used heretofore.

The invention may be briefly summarized as consisting in certain novel arrangements and combinations of parts which will be described in the specification and set forth in the appended claims.

In the accompanying sheets of drawings, Fig. 1 is a side view of the machine embodying my invention; Fig. 2 is a top plan view with the upper hold-down structure removed; Fig. 3 is a fragmentary plan view of the brush supporting parts of the machine; Fig. 4 is a transverse sectional view substantially along the line 4—4 of Fig 1 looking in the direction indicated by the arrow; and Fig. 5 is an end view.

Referring now to the drawings, the machine includes a frame or bed 10, which in this instance is formed of castings, but which may be otherwise formed if desired, there being, however, a main frame portion 10* which supports the major portion of the operating mechanism. Near the top of the machine there is a horizontal elongated platform 11 along which the battery boxes to be brushed are moved, one of these boxes being

shown at B in Fig 1. At the sides of this platform 11 are upstanding guides 12 having inwardly facing flanges on the lower of which the platform 11 is supported. These guides or channels 12 are supported from the bed or frame members beneath by brackets 13, as shown in Figs. 1 and 4.

The battery boxes or other parts to be brushed, are placed on one end of the platform 11 and they are moved along the platform by an endless conveyor consisting of endless side chains 14 which engage end sprockets 15, and cross bars 16 which connect the side chains, one of these cross bars being best shown in Fig. 4. Preferably the upper portions of the chains between the end sprockets 15 slide over the inwardly extended horizontal flanges of angles 17 secured to the inner sides of the channels 12, as best shown in Fig. 4. In the embodiment of the invention here shown, the lower sides of the boxes as they are moved along the platform are subjected to a brushing operation, and therefore the boxes will be placed on the platform with the branded sides downward.

To brush the brands free of carbon or charred wood I utilize in this instance two rapidly rotating cylindrical brushes 18, preferably wire brushes which are disposed at an angle to each other, as clearly shown in Figs. 2 and 3 and are supported beneath the horizontal platform 11 over which the boxes are moved by the conveyor, the platform being provided with a pair of properly disposed slots 19 (see Fig. 2) through which the upper portions of the two brushes project. It may be here stated that by the use of two brushes diagonally disposed and rotated in opposite directions as will be explained subsequently, the brush bristles will be able to enter and thoroughly clean all parts of the depression being cleaned.

When the boxes are moved along the platform over and in contact with the brushes 18, they are definitely positioned with respect to the sides of the platform by being cammed by a yieldable diagonally disposed blade 20 (see Fig. 2) pivotally supported on one of the channels 12, over against the face of a guide strip 21 adjustably supported by brackets 22 from the other channel 12, and additionally while the boxes are being brushed and are being moved over the region of the brushes they are positively held.

downward by a depressor consisting of a frame 23 supported by upstanding brackets 24 mounted on the side channels 12. This depressor, which is gravity actuated and by its weight holds the boxes down against the brushes, preferably consists of a pair of angles 23^a connected together by a pair of cross pins or bars 23^b provided at their ends with rollers 23^c (see Fig. 4) which engage 10 guide grooves or surfaces 24^a in the upright brackets 24.

As best shown in Fig. 1, the angles 23^a of the depressor 23 are provided with straight and normally horizontal middle portions 15 and upwardly inclined ends. The inclined ends towards which the battery boxes are approaching are preferably straight, while the opposite ends are preferably curved, as shown in Fig. 1. The action is as follows:

20 The battery boxes are moved along the horizontal guide 21 towards the slots 19 in the platform 11 through which the brushes project, and when they come under the upwardly inclined ends of the angles 23^a of the 25 depressing frame 23 they tilt the frame upwardly and move under the latter, and while they are pressed down by the straight intermediate portions of the frame they are being brushed, and then the battery boxes ride out 30 from beneath the depressing frame which is then lowered or in position to be acted on or elevated by the next battery box. As shown in Fig. 1, the guides 24^a of the upright brackets 24 on which the rollers 23^c act, are 35 curved as shown at 24^a in Fig. 1, the curvature of the two guides being such that the frame 23 may readily tilt upward at one end while the battery box slides under the frame and then pass beneath the frame by 40 allowing the end which was first elevated to be lowered, and finally the curved end to be lowered to the position shown in Fig. 1. That is to say, the frame is first tilted up 45 at one end and then assumes an upper horizontal position on the box and stays in that position and presses the box down while it is being brushed, and then the forward end which was first elevated is lowered, and then the rear end drops down to the position 50 shown.

For the purpose of rotating the brushes at high speed and also operating the conveyor, I utilize a motor 25 which is supported on the frame or body member 10^a. The shaft of the motor has a pinion 26 which engages a pinion 27 on a shaft 28 having a bevel gear 29 and behind the bevel gear a spur gear 29^a not shown. The spur gear drives a gear 30 on a shaft 31 having a sprocket wheel 32 which by means of a sprocket chain 33 drives the conveyor.

The bevel gear 29 engages a bevel gear 34 on a vertical shaft 35 extending upward along one side of the frame. At the top of 60 the vertical shaft 35 is a bevel gear 36 en-

gaging a bevel gear 37 on the shaft 38 of one of the brushes 18, as shown in Figs. 1 and 3. Thus one of the brushes is driven, and it in turn drives the other brush through bevel gearing 39 at the far end of the two 70 brushes where the shafts are adjacent each other as shown in Fig. 3. This arrangement causes the brushes to rotate in opposite directions.

It is highly desirable that the pressure of 75 the brushes against the boxes be made adjustable or variable, and therefore in accordance with my invention the brushes can be raised or lowered without disturbing the drive above described. To bring this about, 80 the shafts of the two brushes at their adjacent ends are supported in bearings 40, and at their ends which are relatively far apart they are supported in bearings 41, the bearings 40 and 41 being carried by a horizontal 85 plate 42 which is adapted to be raised and lowered. This plate 42, which is shown in both Figs. 3 and 4, is supported from a fixed horizontal plate 43 beneath it through the medium of a series of screws 44, the plate 43 being supported on the frame of body member 10^a. The upper ends of the screws 44 extend freely into sockets of the upper plate 42, but their lower portions are threaded and engage in threaded openings of the lower plate 43. It will be seen, therefore, that it will only be necessary to turn these screws 90 so as to raise or lower them to raise or lower the plate 42 and the brushes 18. To bring this about the middle portions of the screws 95 are provided with pinions 45 (see Figs. 3 and 4) which pinions are engaged by a gear 46 journaled on a central vertical stud 47 of the lower plate 43, this gear 46 carrying on its under side a bevel gear 48 engaged by 100 a bevel pinion 49 on a horizontal shaft 50 which projects out from the side of the machine and is provided with an adjusting hand wheel 51.

Therefore, if to bring about the desired 110 results a more severe brushing action is desired, the operator will turn the hand wheel 51 so as to elevate the brushes, or if a less severe brushing action is desired, the operator will turn the hand wheel so as to lower 115 the brushes.

In order that the elevation of the brushes may be varied by turning the hand wheel 51, one of the bevel gears on the shaft 35, preferably the lower gear 34 is supported independently of the shaft 35, and the shaft has a splined or sliding connection with this bevel gear so that the distance between the lower and upper bevel gears 36 may vary as the 120 adjustment takes place.

Having described my invention, I claim:

1. In a machine of the character described, a platform along which the articles to be brushed are moved, a brush projecting 125 through the platform, and a vertically mov- 130

able gravity actuated depressor under which the articles move and which serves to hold the articles down against the brush during the brushing operation.

5. 2. In a machine of the character described, a platform along which the articles to be brushed are moved, a brush projecting through the platform, and a vertically movable gravity actuated depressor under which
- 10 the articles move and which serves to hold the articles down against the brush during the brushing operation, said depressor comprising a frame supported at opposite sides of said platform and having an inclined
- 15 forward end.
3. In a machine of the character described, a platform along which the articles to be brushed are moved, a brush projecting through the platform, and a vertically movable gravity actuated depressor under which
- 20

the articles move and which serves to hold the articles down against the brush during the brushing operation, said depressor being supported at opposite sides of said platform and having members provided with a 25 straight middle portion.

4. In a machine of the character described, a platform along which articles to be brushed are moved, a rotating brush projecting through the platform and adapted to contact 30 with the entire under surface of the article being brushed, a yielding depressor under which the articles move, and means extending along the platform for definitely positioning the articles relative to the depressor 35 as they move under the same.

In testimony whereof, I hereunto affix my signature.

HENRY W. LORMOR.
